UNITED STATES PATENT OFFICE.

CLIFTON B. CORELL, OF NEW YORK, N. Y., ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,346,367.

Specification of Letters Patent. Patented July 13, 1920.

Application filed November 21, 1918. Serial No. 263,481.

To all whom it may concern:

Be it known that I, CLIFTON B. CORELL, a citizen of the United States, residing in New York city, in the county of New York 5 and State of New York, have invented certain new and useful Improvements in Combined Typewriting and Computing Machines, of which the following is a specification.

10 This invention relates to combined typewriting and computing machines, and is herein disclosed as applied to a machine of the Underwood Addendagraph type having not only a typewriting carriage but also a 15 cross-adding carriage, and means for connecting the two carriages at adjustable predetermined positions.

In such machines, one form of which is disclosed in application of Henry L. Pittman, No. 186,098, filed August 14, 1917, 20 there is usually provided a rack bar having settable column-stops thereon, and a second rack bar having settable dogs thereon, the latter rack bar being adapted to pick up by 25 its set dogs the cross-adding carriage. In the form of the machine disclosed in said application, there are provided two setting arms, one to set the stops or dogs on each rack bar.

30 According to the present invention, a single device may serve as a finger-piece for setting the stops or dogs on either of the rack bars, the way in which the finger-piece is manipulated determining on which rack 35 bar the setting may take place. To effect this, it has been found advantageous to provide a single shaft which may be rocked in one direction to set the column-stop on one rack bar, and in the other direction to set 40 the stop or dog on the other rack bar. For rocking this shaft, the finger-piece may advantageously take the form of a lever at the side of the machine adapted to be rocked either forwardly or backwardly.

45 Other features and advantages will hereinafter appear.

In the accompanying drawings,

Figure 1 is a sectional side view of an Underwood Addendagraph, largely diagrammatic, showing the present invention 50 as applied thereto.

Fig. 2 is a skeleton perspective, showing many of the parts illustrated in Fig. 1.

Fig. 3 is a side view of the setting devices

shown in Fig. 1, but seen from the opposite 55 side and at the moment of setting a cross-adding dog.

Fig. 4 is a view similar to Fig. 3, but showing the devices in the act of setting a 60 column-stop only.

Fig. 5 is a rear view of the pick-up devices for the cross-adding carriage.

Alphabet keys 15 and numeral keys 16, when depressed, swing key-levers 17 to rock bell-crank 18 about a fulcrum rod 19, to 65 swing type-bars 20 upwardly and rearwardly about a fulcrum 21, to cause types 22 to strike against the front side of a rotatable platen 23. The platen 23 is mounted for line-spacing movements, of a work- 70 sheet, not shown, on a carriage 24, which travels back and forth on a front rail 25 and a rear rail 26.

For its letter-feeding movements, the carriage 24 is provided with a feed-rack 27 75 which meshes with a pinion 28 to rotate the latter. The pinion 28 is connected to rotate an escapement wheel 29 by the usual one-way acting pawls 30. The escapement wheel 29 is provided with teeth 31, which alternately engage with a loose dog 32 and a fixed dog 33 on a dog-rocker 34 when the latter is vibrated by a universal bar 35, engaged by heels 36 of the type-bars 20 when the latter approach the printing point. The 80 upper end of the dog-rocker is returned to its forward or normal position, as in the Underwood typewriter, by the usual spring (not shown).

The carriage 24 may be rapidly moved to 90 bring any denominational position of a column on the platen to the printing point. To do this, there is provided a series of tabulator-keys 37, any one of which, when depressed, swings an associated lever 38 to move a plunger 39 to bring the upper end thereof, comprising a denominational stop 40, into the path of effectively-set column-stops 41 on a stop-bar 42 secured to the typewriter carriage by brackets 43. The 95 usual rack-releasing means including the short universal bar 44 may be actuated by the usual heels 45, so that the plungers 39 will draw down the usual link 46, and thereby rock the lever 47 to lift the rack 27 out 100 of the pinion 28. This lifting of the rack 27 frees the carriage from the escapement wheel 29 and permits the usual spring drum

48 to draw the carriage along to the left until it is arrested by the said stop 41.

Computing may be accomplished by the numeral keys 16, each being provided with 5 a differential or indexing cam 49, which, through connections, not shown herein, but similar to the connections in the above-mentioned application of Henry L. Pitman, Serial No. 186,098, may turn the usual master-wheel 50, so that as the carriage feeds along the computing wheels 51 in the totalizer 52, they will be engaged and turned *seriatim* by the master-wheel 50. In order 10 to cause the *seriatim* engagement of the computing wheels 51 with the master-wheel, the totalizer 52 forms part of an adding carriage 53 connected by a bracket 54 to the typewriter carriage 24. As illustrated in Fig. 2, there may be a plurality of totalizers 15 52 on the adding carriage 53, adapted to be adjustably positioned thereon.

In addition to the totalizers 52, there is provided a totalizer 55 adapted to effect cross-adding, and operated by a master-wheel 56 which is adapted to engage *seriatim* the computing wheels 57 in the totalizer 55. To operate the master-wheel 56, there may be provided any usual or suitable gearing from the master-wheel 50, said 20 30 gearing comprising, as herein illustrated, a horizontal shaft 58 and a vertical shaft 59 connected by suitable gears 60. In order to enable the numbers computed in the totalizers 52 to be cross-computed in the totalizer 55, there is provided a separate or supplemental adding carriage 61 on which the totalizer 55 is adapted to be adjustably mounted, said carriage 61 comprising a rack 62 meshing with a pinion 63, which latter 40 is adapted to be turned by the travel of the typewriter carriage. To effect this turning, the pinion 63 is fast on the front end of a shaft 64 having at its rear end a pinion 65 meshing with a segment 66 which is adjustably attached to a second segment 67, the latter constantly in mesh with the rack 68 which is adapted to be picked up intermittently by the typewriter carriage.

To effect this intermittent picking up, the 50 rack 68 has pivoted thereon a pick-up member 69 having a notch 70 which may seat itself on any one of a plurality of suitable devices, as stops or dogs 71. These dogs are shown as mounted in a rack-bar 72 on 55 the typewriter carriage, there being a separate dog 71 for substantially every letter-space travel of the typewriter carriage.

The dogs 71 are normally held in an ineffective position, as illustrated in Figs. 2 60 and 4, and are adapted to be set from that position to the effective position shown in Fig. 3, in which position they stand, with their path intersecting a notch 70 on the pick-up member 69, with the result that as 65 the typewriter carriage travels along, a cam

73 will depress the pick-up member 69 against the tension of the spring 74 when struck by the said dog 71. Continued travel of the typewriter carriage will bring the dog 71 over the notch 70 with the result 70 that the spring 74 will raise the pick-up member 69, so that the notch 70 seats itself on the said dog 71 and the carriage 61 travels along step by step with the typewriter carriage. When the typewriter carriage 75 has carried the secondary carriage 61 to the point at which the totalizer 55 clears the master-wheel 56, the pick-up member 69 releases itself from the notch 70, because a pin 75 on the pick-up member 69 strikes a cam 76 adapted to depress the pick-up member 69 sufficiently to cause the cam 73 to be clear of the notch 70. This permits the usual spring 77 to return the secondary or supplemental carriage 61 to its normal position. The spring 74 is not effective directly on the pick-up member 69, but lifts the pick-up member through the lever 78 to which it is attached, said lever comprising a follower 79 which bears against the bottom surface 80 of the pick-up member 69. In order to keep the pick-up member 69 clear of the dogs while the secondary carriage, and consequently the pick-up member, is returning to its normal position, there is provided a 85 stop 81 effective on the lever 78 to limit its throw by the spring 74.

Both the stops 41 and the dogs 71 are adapted to be held in their set positions by means of detent balls 82 which are pressed 100 by springs 83 into notches 84 formed in the dogs 71 and the stops 41.

In order to set the stops 41, there is provided a stop-setting arm or link 86 which is adapted to be depressed by drawing forward a finger-piece 85, with the result that the stop-setting member will cause its setting lug 87 to depress the stop 41 which is beneath it at the moment. On the release of the stop-setting member, the stop is retained in set position by the detent ball 82. The connections between the finger-piece 85 and the member 86 include a link 88 pivotally attached to the finger-piece 85 between the handle 89 thereof, and its pivot 115 90, said link extending rearwardly and slideable at its rear end in a plate 91 screwed to the frame of the machine and provided with an opening 92 which serves as a guide for the link 88. This link moves the stop-setting member because it rocks forwardly the left-hand end 93 of a lever pivoted at 94, so that the right-hand end 95 of the lever will push rearwardly a rock arm 96, fast on a shaft 97, so that a second rock arm 98 on 120 said shaft will pull down the stop-setting member 86 by engaging a heel 99 at the lower end thereof.

The lever end 93 has a very small movement and may engage the link 88 by merely 130

resting in a notch 100 therein which it fits fairly closely, the right-hand end 95 forming a sort of pin-and-slot connection with the rock arm 96. The shaft 97 may be journaled in ears 101 projecting from the usual tabulator-stop frame 102. To guide the stop-setting member 86 vertically, its upper end may ride in a fork formed by a pair of lugs 103 at the top of the tabulator-stop frame, and to prevent it from rocking backwardly, the member may be provided with a slot 104 by which it straddles a fixed shaft 105. The shaft 105 may include collars 105^a to hold the member in the proper vertical plane. In order to hold the stop-setting member normally clear of the stops 41, it is provided with a spring 106 which draws on the end of the slot 104 and may be anchored in any suitable place, as in one of the lugs or ears 103. The lever 93, 95 has its pivot 94 in a bracket 107 fast to the typewriter frame.

If it is desired to set a dog 71, the finger-piece 85 is moved rearwardly with the result that it rocks forwardly a dog-setting arm 108 pivoted at 109 on an ear 110 projecting from the stop frame. The connections for operating the dog-setting arm 108 include a pendant-link 111 connected by a pivot 112 to the forward end of the downwardly-extending arm 113 of the setting arm 108, said pendant being provided with a heel 114 which is adapted to be struck by a third rock arm 115 on the shaft 97 when the finger-piece 85 is moved rearwardly. The two rock arms 98 and 115 may be formed as a single piece. The link 111 may normally hold the dog-setting arm 108 in its rearward or ineffective position, and to accomplish this, the link is provided with a lug 116 to which is attached a spring 117 anchored in the tabulator frame and normally drawing the lug 116 upward. To guide the dog-setting arm 108, it may pass through an opening 118 in the tabulator-stop frame.

Since it is almost always desirable to set a stop 41 whenever a dog 71 is set, there may be provided a connection whereby the dog-setting arm will always operate the stop-setting arm 86. As herein disclosed, the connection includes a lug 119 on the link 111 which overlies a lug 120 on the stop-setting member 86. In order to set the stop 41 and the dog 71 at the proper letter-space, the setting members therefor are set near the center of the machine, and the finger-piece 85, for convenience, is placed at the end of the machine,—the lever 93, 95 and the shaft 97 serving to transmit motion from the end to the center of the machine. For the purpose of resetting the stops 41, there is provided a resetting slide 121 comprising diagonal, cam-shaped openings 122 engaging screws or pins 123 on the stop-

bar, so that mere pushing of the slide 121 endwise will reset the stops. The dogs 71 are adapted to be reset by a similar slide 124 having cam openings 125 engaging pins 126. As a further means for steadyng the 70 dog-setting member 108, there is provided on the rear of the tabulator casing a pair of lugs 127, which prevent the link 111 from moving sidewise, and have a base 128, which is adapted to prevent the link 111 75 from being drawn rearwardly by the spring 117.

Variations may be resorted to within the scope of the invention, and portions of the improvements may be used without others. 80

Having thus described my invention, I claim:

1. In a typewriting machine, the combination with a pair of bars, each carrying a series of settable stops, of a stop-setting device 85 for each of said series, including a movable member through which the device is actuated, and an actuating piece mounted so that movement in one direction will effect actuation of one of said movable members, and 90 movement in another direction will effect actuation of the other of said movable members.

2. In a typewriting machine, the combination with a pair of bars, each carrying a series of settable stops, of a stop-setting device 95 for each of said series, including a movable member through which the device is actuated, an actuating piece mounted, so that movement in one direction will effect actuation of one of said movable members, and movement in another direction will effect actuation of the other of said movable members, and means, including a lug on one of said movable members, whereby actuation 100 of said lug-carrying member will effect actuation of the other.

3. In a typewriting machine, the combination with two sets of settable dogs or stops, of a finger-piece and means actuated by said 110 finger-piece when moved in one direction to set a stop in one set, and in the other direction to set a stop in the other set.

4. In a typewriting machine, the combination with a traveling carriage and column 115 stops, of a supplementary carriage, means, including settable dogs, for causing the two carriages to travel together, a single finger-piece, and means selectively operable by said finger-piece for setting both the stops and 120 the dogs.

5. In a typewriting machine, the combination with a traveling carriage and column stops, of a supplementary carriage, means, including settable dogs, for causing the two 125 carriages to travel together, a single finger-piece and means selectively operable by said finger piece for setting stops or for setting stops and dogs.

6. In a typewriting machine, the combina-

- tion with two sets of settable devices, of a setting member for each, a rock shaft, an arm on said shaft for operating one setting member when turned in one direction, and a 5 second arm for operating the other setting member when turned in the other direction.
7. In a typewriting machine, the combination with two sets of settable devices, of a setting member for each, a rock shaft, an 10 arm on said shaft for operating one setting member when turned in one direction, a second arm for operating the other setting member when turned in the other direction, and means whereby operation of one setting 15 member operates the other.
8. In a typewriting machine, the combination with two sets of settable devices, of a setting device for each, including a member through which said device is actuated, a rock 20 shaft, means, including an arm on said shaft, for operating one member when said shaft is turned in one direction, means, including a second arm, for operating the other member when said shaft is turned in the other direction, means whereby operation of one member operates the other, a single finger-piece, and means controlled by said finger-piece for turning said shaft in either direction.
13. In a typewriting machine, the combination with two sets of settable devices, of a setting device for each, including a member through which said device is actuated, a rock shaft, means, including an arm on said shaft, for operating one member when said shaft is turned in one direction, means, including a second arm, for operating the other member when said shaft is turned in the other direction, means whereby operation of one member operates the other, a single finger-piece, and means controlled by said finger-piece for turning said shaft in either direction.
14. In a typewriting machine, the combination of a carriage, a plurality of sets of settable devices, a single key differently movable, and means actuatable by said key to selectively set a stop in one of said sets of devices or one in each set of devices.
15. In a typewriting machine, the combination with two sets of settable dogs, of a setting device for the dogs of each set, including a member through which said device is actuated, a rock shaft, an arm on said shaft for operating one of said members when said shaft is turned in one direction, and a second arm for operating the other member when said shaft is turned in the opposite direction.
16. In a typewriting machine, the combination with two sets of settable dogs, of a setting device for the dogs of each set, including a member through which said device is actuated, a rock shaft, an arm on said shaft for operating one of said members when said shaft is turned in one direction, a second arm for operating the other member when said shaft is turned in the opposite direction, and means whereby operation of one of said members will effect operation of the other.
17. In a typewriting machine, the combination with a series of settable column-stops and a series of pick-up dogs, of a setting device for each series, including a member through which said device is actuated, a heel on each of said members, and a pivotally mounted element comprising an actuating arm for each of said members overlying the same, whereby movement of said element in one direction will cause actuation of one of said members by engagement with the heel thereon, and movement of said element in the other direction will effect actuation of the other member.
18. In a typewriting machine, the combination with a series of settable column-stops and a series of pick-up dogs, of a setting device for each series, including a member through which said device is actuated, a heel

on each of said members, a pivotally mounted element comprising an actuating arm for each of said members overlying the same, whereby movement of said element in one direction will cause actuation of one of said members by engagement with the heel thereon, and movement of said element in the other direction will effect actuation of the other member, and means whereby actuation 10 of one of said members will effect actuation of the other.

19. In a typewriting machine, in combination, a traveling carriage, a plurality of series of settable stops mounted on said carriage, a finger-piece movable to different positions, and means operable by said finger-piece for selectively setting a stop in one of said series or one in each series, the stops set in each series being dependent upon the

letter-space position of the carriage at the 20 time the setting is effected.

20. In a typewriting machine, in combination, a plurality of sets of settable dogs, a dog-setting device for each set adapted to set one dog at a time, means to enable a relative 25 traveling movement between said sets and said dog-setting devices, to determine the stops with which said setting devices are in operative relation, a single finger-piece movable to different positions, and means operable by movement of said finger-piece to different positions to set a stop in one of said sets of dogs or one in each set. 30
